UNITED STATES PATENT OFFICE.

HIRAM H. HIRSCH, OF PHILADELPHIA, PENNSYLVANIA.

DESIGN FOR A FRAME AND SUPPORT FOR ELECTRIC FANS.

41,848.

Specification for Design.

Patented Oct. 17, 1911.

Application filed April 19, 1909. Serial No. 490,974. Term of patent 7 years.

To all whom it may concern:

Be it known that I, HIRAM H. HIRSCH, a citizen of the United States, residing at Philadelphia, in the county of Philadelphia and State of Pennsylvania, have invented a new, original, and ornamental Design for a Frame and Support for an Electric Fan, of which the following is a specification, reference being had to the accompanying drawing, forming a part thereof.

The figure is a perspective view showing my new design.

I claim.

The ornamental design for a frame and support for an electric fan, as shown.

HIRAM H. HIRSCH.
